CLAIM

The ornamental design for a low profile light, as shown and described.

DESCRIPTION

FIG. 1 is a perspective view of a low profile light according to an embodiment of the present invention.

FIG. 2 is a top plan view of the low profile light illustrated in FIG. 1.

FIG. 3 is a bottom plan view of the low profile light illustrated in FIG. 1.

FIG. 4 is a side elevation of the low profile light illustrated in FIG. 1.

FIG. 5 is a perspective view of a low profile light according to an embodiment of the present invention.

FIG. 6 is a top plan view of the low profile light illustrated in FIG. 5.

FIG. 7 is a bottom plan view of the low profile light illustrated in FIG. 5; and,

FIG. 8 is a side elevation view of the low profile light illustrated in FIG. 5.

The broken lines depict elements of the low profile light that do not form a claimed feature of the present invention.
